CLAIM

The ornamental design for a running board for vehicles, as shown and described.

DESCRIPTION

FIG. 1 is a top perspective view of a running board for vehicles showing our new design;

FIG. 2 is a top view thereof;

FIG. 3 is a rear view thereof;

FIG. 4 is a front view thereof; and,

FIG. 5 is an exploded top perspective view of the running board for vehicles shown in FIG. 1.

The ornamental design which is claimed is shown in the solid lines in the drawings. The broken lines shown in the drawings are for the purpose of illustrating environmental structure and form no part of the claimed design.
